CLOCK ILLUMINATION

Philip Konopitski, Buckroe Beach, Va.

Application January 30, 1942, Serial No. 428,946

1 Claim. (Cl. 240—2.1)

This invention relates to clock illumination, and has for the primary object the provision of an efficient and inexpensive portable device of the stated character, which will provide a simple and practical support for a clock to permit positioning thereof at any place desired and provides accommodation for a source of electrical energy and electric illuminating means for the face of the clock, whereby a person desiring to ascertain the time in the dark may conveniently render the illuminating means operative and thus be able to clearly read the time, the electric illuminating means automatically becoming inoperative immediately on being free of manual operation.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a front elevation illustrating a clock illumination constructed in accordance with my invention.

Figure 2 is a top plan view illustrating the device.

Figure 3 is a fragmentary front elevation, partly in section, showing the mounting of the source of electric energy and the control switch for the electric circuit between said source and the electric lamp.

Figure 4 is a fragmentary bottom plan view, partly in section, illustrating the mounting for the source of electric energy.

Figure 5 is a fragmentary sectional view illustrating the electric illuminating means and its mounting.

Figure 6 is a fragmentary front elevation illustrating a modified form of my invention.

Referring in detail to the drawings, the numeral 5 indicates the body of the device which may be of various shapes or designs and is preferably provided with a flat bottom face 6 to permit the body to rest evenly upon any type of support, such as a table, shelf, mantel or the like.

The body 5 may be constructed of any material suitable for the purpose and is provided with an opening 7 to provide a mounting for a clock 8. Any type of clock, either electric or spring operated, may be mounted in the body and arranged above the face of the clock on the front wall of the body is a reflector 9 to accommodate therein an electric lamp 10. The reflector acts to direct

the rays of light from the electric lamp over the face of the clock so that it can be read for a considerable distance in the dark.

5 The body 5 is provided with a recess 11 for the accommodation of the electric lamp socket 10', the conductors of which are indicated by the character 12. The electric lamp socket extends a limited distance outwardly of the recess 11 to support the electric lamp 10 within the reflector 9.

10 The body 5 is provided with a passageway 13 leading from the socket 10' to a chamber 14 opening outwardly through one end of the body and through which extend the electric conductors.

15 A self-releasing push button type switch 15 is mounted on the body 5 and extends into the chamber to contact a battery 16 when manually pressed. One of the conductors is electrically connected to the switch 15 while the other conductor is connected to an electric contact 17 of the spring type mounted in the chamber 14, as shown at 18. The spring contact 17 bears against the battery 16.

20 The battery 16 is removably mounted in a holder 19 carried by a closure plate 20 acting normally to close the chamber 14 and is provided with a finger piece 21 to permit a person to readily remove the holder 19 when it is necessary to renew the battery.

25 The holder 19 is of substantially U shape providing spring arms 22 and a connecting portion 23 for the spring arms. The connecting portion 23 is suitably secured to the plate 20. The free ends of the spring arms are preferably curved away from each other to facilitate the application of a battery to the holder. Said spring arms include ears 24 which engage under the lower end of the battery and coact with the arms in firmly supporting the battery within the chamber 14 in engagement with the spring contact 17.

30 The battery 16 is preferably of the flashlight type and when mounted in the holder 19 and the latter located within the chamber 14, the contact of the battery will be located directly under the switch 15 so that when the latter is pressed manually the circuit to the electric lamp will be completed and thereby efficiently illuminate the face of the clock carried by the body of the device.

35 The spring arms 22 are provided with offsets 26 to enter grooves formed in opposite walls of the chamber 14 to releasably secure the holder 19 in the chamber.

40 The switch 15 is of the spring plunger type and the housing thereof frictionally fits within an

opening provided in the body and which communicates with the chamber 14. The spring of the plunger normally positions the latter away from the contact of the battery, consequently breaking the circuit to the electric lamp.

When a person desires to ascertain the time in the dark, it is only necessary to press the plunger of the switch and the dial of the clock becomes fully illuminated permitting the person to clearly ascertain the time.

Referring to my modified form of the invention, the shape of the body may be varied from that described heretofore and is indicated generally by the character 27. The body 27 has a recess 28 opening outwardly through its upper end. A portion of the recess 28 is larger than its other portion, the smaller portion of the recess being for the accommodation of the battery holder, as clearly shown in Figure 6. The portions of the body 27 where the recess 28 opens outwardly through the upper end of said body provide spaced rests 29 on which a clock 30 may rest. In this form of the invention the reflector and electric lamp are mounted on the front face of the body 27 to direct the rays of light upwardly over the face of the clock when the switch is pressed.

From the foregoing description taken in connection with the accompanying drawings it will be seen that a very efficient holder or support has been provided for a clock, which will accommodate electric illuminating means as well as the source of energy for said illuminating means

with a switch whereby the circuit of the electric illuminating means may be manually closed when desiring to illuminate the clock supported by the holder.

5 A device of this character will be found extremely useful and may be manufactured and sold at a low cost.

While I have shown and described the preferred embodiment of my invention, it will be understood that minor changes in construction, combination and arrangement of parts may be made without departing from the spirit and scope of the invention as claimed.

10 Having thus described my invention, what I claim is:

15 In a clock illuminating device, a body including a clock seat, an electric lamp for illuminating a clock mounted on said body, a reflector for said lamp and carried by the body, said body having a chamber opening outwardly through an end of the body, a holder including a face plate and resilient fingers for receiving and gripping a battery to support the latter within said chamber with the face plate closing said chamber, an electric circuit including a switch electrically connecting the battery to the electric lamp with the switch mounted in said body for manual operation from the exterior thereof, said fingers having binding engagement with walls of the chamber 20 to releasably secure the holder therein.

25 PHILIP KONOPITSKI.
